Des. 227,380
Patented June 19, 1973

227,380

PLAYGROUND EQUIPMENT FRAME

Erwin N. Korte, Carbondale, and Donal D. Hock, Herrin,
Ill., assignors to Mattel, Inc., Hawthorne, Calif.

Filed Nov. 17, 1971, Ser. No. 199,823

Term of patent 14 years

Int. Cl. D21—03

U.S. Cl. D34—5 M

FIG. 1

FIG. 2

FIG. 3

FIG. 4

FIG. 5

FIG. 6

FIG. 7

FIG. 1 is a perspective view of the playground equipment frame showing our new design;

FIG. 2 is a front view thereof;

FIG. 3 is a left side view thereof;

FIG. 4 is a top plan view thereof;

FIG. 5 is a right side view thereof;

FIG. 6 is a rear view thereof; and

FIG. 7 is a bottom plan view thereof.

We claim:

The ornamental design for a playground equipment frame, as shown.
